United States Patent Office.

W. R. POMEROY, OF MILLERSBURG, OHIO.

Letters Patent No. 90,388, dated May 25, 1869.

IMPROVED DENTAL INSTRUMENT.

The Schedule referred to in these Letters Patent and making part of the same.

To all whom it may concern:

Be it known that I, W. R. POMEROY, of Millersburg, in the county of Holmes, and State of Ohio, have invented certain new and useful Improvements in Dental Instruments; and I do hereby declare that the following is a full and complete description of the same, reference being had to the accompanying drawings, making a part of this specification, in which—

Figure 1 is a side view of the instrument.

Figure 2, a view of the front edge.

Like letters of reference refer to like parts in the several views presented.

This invention relates to a dental plugger, for condensing a filling of metallic foil in the cavity of a tooth, the power being applied by a succession of blows given by a mallet, the same being operated by a finger of the hand holding the instrument, the degree of force required being regulated by an adjusting-screw, herein-after more fully described.

In fig. 1, A represents a bracket, on the front edge of which is secured a sleeve, or socket, B, in which is inserted the shaft C of an ordinary plugging-instrument, and secured therein by a thumb-screw, D.

To the extreme rear end of said bracket is pivoted an arm, E, having a hammer or mallet, O, attached to the free end of the same.

Also attached to the bracket is a stay, F, to serve as a support for the screw a.

H is a coiled spring, the coiled end of which is secured to the bracket, whereas the upper, or free end is attached to the arm through the intervention of the link I and collar J, to which it is pivoted, thereby making an easy and flexible joint.

K is a cord, one end of which is attached to the mallet, whereas to the other is secured a thimble, L, the purpose of which will be presently shown.

Having thus described the construction and arrangement of the instrument, the practical operation of the same is as follows, viz:

The operator holds the instrument between the thumb and first two fingers, below the sleeve referred to, or at such other point as may be the most convenient, in order for a proper application of the point of the instrument to the tooth.

The position of the instrument is such that the articulation of the arm E will be toward the operator, which will bring the cord across the back of the fingers. The end of the small one is inserted in the thimble, whereby the hammer is operated for giving the blows upon the upper end of the plugger from time to time, as the operator may require, the force of the blows being regulated by the power applied by the finger, also by the distance that the mallet falls from its elevation, shown in fig. 1, to the end of the plugger, said distance being lengthened or shortened by the adjusting-screw a in the upper end of the stay F, through which it passes, and contacts with the arm E,

against which it will strike on being screwed down, thereby shortening the stroke, and lessening the force of the blow more or less, according to the distance that the screw may be turned down.

It will be obvious, that in consequence of the peculiar arrangement of the spring and link H I, the greatest resistance of the spring is obtained on the first start of the mallet, and, as the link approaches a horizontal line, the leverage increases, thereby operating the mallet more easily and with greater effect than if the resilience of the spring continued until the striking of the mallet. By this means, a more delicate and varied succession of blows can be given, thereby making the instrument much more effective in the hands of the operator than the automatic plugger and other instruments of this class now in use by the dental profession, as in such instruments the blow is usually given by a spring, which is operated by pressing the point of the instrument upon the foil in the cavity, and, in consequence of the continued resistance of the spring until the blow is given, it is a matter of much difficulty to regulate its intensity, whereas in this instrument the intensity of the blow is regulated and controlled by means of the set-screw a, and by operating the mallet independently, by means of the finger.

I am aware that a mallet has been used in combination with a plugger. This I do not claim. But that which distinguishes my invention from others is the special arrangement of the spring and lever-link H I, whereby the resistance of the spring is overcome by the increase of the power of the link, or lever, in proportion as the mallet approaches the end of the plugger, thereby giving the operator greater control over the instrument, for regulating the force of the blow, than can be exercised over those now in use. Also, operating the mallet independently, by the finger, by means of the cord and thimble, the particular advantage of which is, that a blow can be given with or without pressure, or pressure without a blow, at any time, and of any required degree of intensity, at the will of the operator.

Another advantage in my invention, over others, is that an ordinary dental hand-plugger is used, instead of a short point made expressly for the instrument. The expense is, therefore, greatly reduced, so that the dentist is enabled to use, in connection therewith, the same kind of plugging-instruments which are now used by hand-pressure, or with the mallet and assistant.

What I claim as my invention, and desire to secure by Letters Patent, is—

The adjusting-screw a, yoke F, arm E, bracket A, mallet G, and plugger C, combined and arranged to operate in the manner substantially as described, and for the purpose specified.
